JULIAN O. ELLINGER, OF NEW YORK, N. Y.

COLLAPSIBLE FRAME FOR CONCRETE CONSTRUCTION.

1,094,842.

Specification of Letters Patent. Patented Apr. 28, 1914.

Application filed November 23, 1911. Serial No. 661,876.

To all whom it may concern:

Be it known that I, JULIAN O. ELLINGER, a citizen of the United States, and a resident of the city, county, and State of New York, have invented certain new and useful Improvements in Collapsible Frames for Concrete Construction, of which the following is a specification.

This invention relates to reinforcements for concrete beams, girders etc. and consists of the peculiarities of construction and novel combinations and arrangements of parts disclosed by the accompanying drawings and the following description.

The objects or purposes of the invention and its advantages will fully appear from the following description of the form thereof selected to exemplify the best embodiment thereof known to me, but, as will hereinafter more fully appear, changes in the details may be made without departing from the spirit of the invention or its scope as defined by the subjoined claims.

In the accompanying drawings:—Figure 1 is a side elevation of a concrete reinforcing frame exemplifying a very desirable form of my present invention; showing in dotted outline the frame folded or collapsed for transportation or storage and in full lines said frame expanded for use. Fig. 2 is a plan view of the reinforcement expanded for use. Fig. 3 is a vertical section through the reinforcement showing the same on a larger scale than the preceding figures and 35 in position in a form, the line of section upon which the reinforcement is taken being indicated at 3—3 on Fig. 1. Fig. 4 is an end view of the reinforcement, collapsed. Fig. 5 is a detail representation showing a 40 means for connecting a link and a stop or centering device to a longitudinal member of the reinforcement, different from that disclosed in the preceding figures and Fig. 6 is an inverted plan view of the parts shown 45 in Fig. 5.

Similar characters of reference denote corresponding parts in the several views.

The reinforcement constituting the present invention comprises a frame A composed of spaced longitudinal members which are connected with each other by transverse members pivoted to permit the frame to be collapsed for convenience in transportation and storage and expanded for use. In the 55 particular embodiment of the invention herein illustrated to exemplify a most de-

sirable form thereof one of the longitudinal members, marked 20, is continuous throughout the length of the frame, while the other comprises two sections 21 and 22 respectively, which are spaced from each other and from the member 20, a third member or section 23 being in such case preferably so disposed that it will span the space between the confronting ends of the sections 21 and 22 and lie between the planes of the latter sections and the member 20.

The pivoted transverse elements of the frame in the herein-illustrated embodiment of the invention comprise two series of 70 spaced-apart links marked 24 and 25 respectively, the series of links 24 serving to connect the longitudinal section 21 with the member 20 while the series of links 25 connect the longitudinal section 22 with said 75 member 20. Preferably, when the frame is expanded for use the links are inclined or diagonally disposed and preferably also the series of links 24 are inclined or diagonally arranged oppositely to the series 80 of links 25, as shown. It further is considered to be preferable to have the sections 21 and 22 extending to a place outward beyond the ends of the member 20.

A very advantageous manner of connecting the parts consists in pivoting the ends of the links to elements which are weldably united to the longitudinal members of the frame, contradistinguished from pivoting the links directly to the longitudinal members. The elements for connecting the links to the longitudinal members, illustrated in the accompanying drawings consist of arms 26 extending transversely of said members and projecting beyond the surfaces of the 95 same, the links being pivoted to the projecting portions of said arms, as shown at the places marked 27. Certain of these arms also serve to rigidly connect the longitudinal member or section 23 to the member 20, 100 being welded to both of the same.

The welds hereinbefore referred to are preferably electric welds and a very desirable form of longitudinal members therefor is illustrated, attention being called to the 105 fact that each of said members is composed of a bar rolled to produce spaced longitudinal ribs 28, 28 thereon, said ribs serving as means by which the arms 26 may be welded flatwise to the longitudinal members. Other 110 forms of welding projections than the ribs referred to and other forms of arms 26 than

the flat ones herein referred to may, however, be employed if desired.

The foregoing frame may be sufficient in some cases, but in many instances it will be found to be desirable to provide a reinforcement consisting of a plurality of such frames connected to each other. This is exemplified in Figs. 2, 3 and 4, wherein A designates one frame and B another. These frames are connected with each other, preferably at both top and bottom, by links 29 whereby they may be folded together, as shown in Fig. 4. The links are preferably connected to the longitudinal members of the frame by means of arms 30, weldably united to said members in the manner already described with reference to the links 24 and 25. The pivots by which the links 29 are connected to the arm 30 are marked 31. This provides a very desirable construction of reinforcement, the two frames connected in the manner described forming a hollow skeleton reinforcement having longitudinal members which are connected together on all sides of the reinforcement by pivoted transverse elements which are adapted to permit the longitudinal members to move relatively to each other into or from a compactly collapsed condition.

It will be noted that the foregoing construction constitutes a very desirable embodiment of a concrete reinforcement having spaced longitudinal elements, forming tension members, which are connected to each other by spaced transverse elements, forming shear members, in such a manner that the frame may be collapsed into small compass for transportation and storage and readily opened out into its expanded form for use.

Particularly should it be noted that in the particular embodiment herein illustrated the two sections 21 and 22 of one of the longitudinal members move toward each other as well as toward the member 23, in collapsing the frame so that when the frame is collapsed in the sections 21 and 22 lie against or adjacent to the member or section 23 throughout a part of their length, whereby when the frame is collapsed it is reduced both longitudinally and transversely as compared with its longitudinal and transverse dimensions when it is expanded. Preferably the extent of the movement of the sections 21 and 22 toward each other is such that when the frame is collapsed the outer ends of the sections 21 and 22 will not project beyond the ends of the member 20.

It further will be noted that the illustrated manner of connecting the links to the longitudinal members contributes to the formation of an economically produced and strong and durable frame; and again it will be particularly noted that an especially effective reinforcement is produced by the use of the

connected frames and that by pivotally connecting the longitudinal members of each frame with each other and pivotally connecting the frames themselves with each other, substantially in the manner hereinbefore set forth, a very effective reinforcement is produced which may be folded in intersecting planes, first to bring the longitudinal members of each of two sides thereof close to each other and, second, to bring said two sides together.

It obviously is preferable in practice to provide means which define the position of the parts when the frame is properly expanded and will prevent their being moved beyond such position by any force applied thereto. This may be accomplished in any approved manner or by any approved means. The means herein shown for the purpose comprise stops 32 and 33 on the member 23 arranged to engage the links 24 and 25 respectively.

In Fig. 3 there is shown a reinforcement of the construction hereinbefore described mounted in a form C for a beam or girder. In addition to the elements already described the reinforcement will be seen to be provided with stops or centering devices having members 34 and 35 arranged at an angle with each other. The members 34 rest upon the bottom of the form and the members 35 engage the inner walls of the form. These stops or centering devices thereby define the position of the reinforcement in the form and hold it in proper position while the concrete is being supplied and is setting around the reinforcement. Each of these stops or centering devices is preferably of L-form and each may be weldably united to the adjacent longitudinal member, as shown best in Fig. 3, in which the bars 20, 20 are shown as being provided with welding projections 36 whereby the stops or centering devices may be electrically welded thereto. In Figs. 5 and 6, however, there is shown a stop or centering device which is pivotally mounted so that it may be turned to occupy a plane parallel with the bar 20 when the frame is collapsed. The members of this stop or centering device are marked 34^a and 35^a respectively and they are shown as being pivoted at 34^b to an arm 35^b which is electrically welded to the longitudinal members 20, the latter being provided with welding ribs 20^a as shown. In this particular embodiment of the invention the arm 35^b is formed integral with and projects angularly from an arm 26^b which serves as the means by which the links 24 or 25 are connected to the members 20, 21 or 22.

Having now described the invention what I believe to be new and desire to secure by Letters Patent and what I, therefore, claim, is:

1. A concrete reinforcing frame, com-

130

prising a longitudinal member, sections extending longitudinally of the frame, two of said sections being arranged at opposite sides of the center of said longitudinal member and being provided with links for pivotally connecting them to the latter and another of said sections being arranged between the first mentioned sections and substantially parallel with and adjacent to the longitudinal member and in position to span the space which is between the confronting ends of the other sections when the frame is expanded.

2. A concrete reinforcing frame, comprising a longitudinal member, sections extending longitudinally of the frame, two of said sections being arranged at opposite sides of the center of said longitudinal member and being provided with links for pivotally connecting them to the latter and another of said sections being arranged between the first mentioned sections and the longitudinal member and in position to span the space which is between the confronting ends of the other sections when the frame is expanded, said third section being rigidly connected to said longitudinal member and the links being so disposed that they will extend divergently from said longitudinal member to the respective sections when the frame is expanded.

3. A concrete reinforcing frame comprising a longitudinal member, sections extending longitudinally of the frame and arranged at opposite sides of the center of said member, links having pivot connections with said member and sections, whereby the frame may be expanded, and fixed stops secured to the longitudinal member for holding the frame in an expanded position.

4. A concrete reinforcing frame, comprising a longitudinal member, sections extending longitudinally of the frame and arranged at opposite sides of the center of said member, links having pivotal connection with said member and sections, whereby the frame may be expanded, and a section which extends longitudinally of the frame and is arranged parallel to and alongside of said member and between the same and said sections and is provided with stops arranged to be engaged by certain of said links to hold the frame in an expanded position.

5. A concrete reinforcing frame, comprising a longitudinal member; sections extending longitudinally of the frame and arranged at opposite sides of the center of said member, spaced elements rigidly secured to said sections and member, respectively and projecting therefrom, a third section extending longitudinally of the frame, said third section being arranged alongside of said longitudinal member and between the same and the first-mentioned sections and being rigidly connected to said member, and

links for connecting the first named sections with said longitudinal member, said links having their ends pivotally secured to the projecting portions of said elements.

6. A collapsible concrete reinforcing frame, comprising a longitudinal member, sections extending longitudinally of the frame and arranged at opposite sides of the center of said member, links pivotally connecting said sections to said member, and centering devices pivotally connected to one side of said member to be turned from a position transverse to and parallel with the longitudinal member for the purposes described.

7. A collapsible concrete reinforcing frame, comprising a longitudinal member, sections extending longitudinally of the frame and arranged at opposite sides of the center of said member, links connecting said sections to said member, and centering devices pivotally connected to said member, each of said centering devices having members which extend approximately at right angles with each other, the centering devices being pivoted to the underside of the longitudinal member to adapt them to be turned into the line of the latter.

8. A concrete reinforcement comprising a pair of frames, each comprising a plurality of longitudinal members having elements rigidly united thereto and projecting therefrom at an angle with each other, links pivotally connecting the members of the frames with each other and other links pivotally connecting the frames together, the latter links being arranged at an angle to the first mentioned links, all of said links having their ends pivoted to the projecting ends of said elements.

9. A concrete reinforcement, comprising a plurality of frames; each of said frames having a longitudinal member, a plurality of sections extending longitudinally of the frame and arranged at opposite sides of the center of the longitudinal member, and links pivotally connecting said longitudinal member and sections together, and a section which extends longitudinally of the frames and is rigidly connected to said longitudinal member between the same and said sections; the reinforcement also having links which connect the frames with each other.

10. A concrete reinforcement, comprising a plurality of frames; each of said frames having a longitudinal member, provided with projections rigidly secured thereto, a plurality of sections provided with projections rigidly secured thereto extending longitudinally of the frame and arranged at opposite sides of the center of the longitudinal member, and links pivotally connecting said sections to the longitudinal member, said links having their ends pivoted to projections of said member and of the sections,

the reinforcement also having links which connect the frames with each other, the latter links being pivoted to projections of the sections and the projections on the member 5 of each of the frames.

11. A concrete reinforcement, comprising a plurality of frames; each of said frames having a longitudinal member, provided with projections rigidly secured thereto, a 10 plurality of sections provided with projections rigidly secured thereto extending longitudinally of the frame and arranged at opposite sides of the center of the longitudinal member, and links pivotally connecting said sections to the longitudinal member, said links having their ends pivoted to projections of said member and of the 15

sections, and a section which extends longitudinally of the frame and is arranged between the longitudinal member and said sections and is rigidly secured to projections of the former; the reinforcement also having links which connect the frames with each other, the latter links being pivoted to projections of the first named sections and the 20 members of the frames. 25

In witness whereof I have hereunto set my hand at the borough of Manhattan, city and State of New York, this 6th day of November, 1911.

JULIAN O. ELLINGER.
